UNITED STATES PATENT OFFICE

CHARLES E. REDFIELD, OF CHICAGO, ILLINOIS

CLEANING DEVICE

Application filed May 4, 1931. Serial No. 534,998.

This invention relates to certain novel improvements in cleaning devices, especially adaptable for cleaning sediment or other foreign matter from air vents of heating radiators and the like, and has for its principal object the provision of an improved construction of this character which will be highly efficient in use.

It is common practice to associate with a steam radiator or the like a device known as an air vent, the purpose of which is well known to those skilled in the art. The air vent embodies, in general, a vent opening, passage through which is normally controlled by a selective valve mechanism which is capable of adjustment to permit emission of air from the radiator when the same becomes air bound or to prevent the radiator from becoming air bound. The expulsion of air or partly vaporized water through this air vent frequently carries with it minute foreign matters or deposits which corrode or collect at the vent opening and consequently close passage therethrough resulting in the air binding of the radiator or the like and resulting in the lack and loss of heat radiation. To overcome this it has been the custom to supplant the inoperative air vent with a new air vent or take the defective air vent apart for the purpose of removing these minute foreign matters or deposits. This results in considerable expense and labor, and oftentimes rather than clean the air vent, the same is completely discarded.

It is, therefore, one of the many objects of this invention to provide a cleaning device which is portable in character, and which may be expeditiously utilized for readily and expeditiously cleaning the air passage and removing the minute foreign matter or deposits therefrom, thus resulting in the saving of time and expense, and the replacement of complete new air vents or parts thereof.

Other objects will appear hereinafter.

The invention consists in the novel combination and arrangement of parts to be herein-after described and claimed.

The invention will be best understood by reference to the accompanying drawing showing the preferred form of construction, and in which:

Fig. 1 is a perspective view of the invention;

Fig. 2 is a sectional detail view taken substantially on line 2-2 of Fig. 1; and

Fig. 3 is a side elevational view of the invention, showing the same partly in section.

The air vent is illustrated generally at 10 and may be of any particular type or design now commercially in use, and which preferably includes a nipple or stem 11 having a threaded portion 12 to facilitate connecting the air vent to the radiator in the usual manner.

The cleaning device embodying my invention includes a body 13 which may be of any conventional or convenient shape or design. This body 13 provides a container for a cleansing liquid 14. As my invention is not concerned with the character of this cleansing material, the same may be of any character such as will best serve the purpose, and such that is offensive to rust or corrosion.

The body 13 is provided with an opening 15 in which is mounted a ring 16, and this ring 16 is provided with an opening 17 threaded to receive the threaded nipple or stem 11. The opposite corresponding side walls 18 of the body 13 are preferably formed of such material as will allow these walls to be manually compressed or buckled inwardly for the purpose of compressing the liquid within the body 13 to expel the same through the air vent 10.

In use, the air vent, when rendered inoperative, is removed from connection with the radiator and threaded to the ring 16. After this is done the opposite corresponding side walls of the body are compressed or flexed inwardly, which compresses the liquid within the body 13 and causes the same to be projected through the vent. The force of expulsion of the liquid will remove any foreign matters or deposits from the vent passage in the air vent 10 and consequently thoroughly cleanse the air vent, rendering the same again operative. After the air vent has been thoroughly cleaned the same is removed from connection with the ring 16, and reconnected to the radiator.

To prevent the liquid from being dis-

charged from the container when not in use, a plug 19 is provided and this plug 19 is threaded into the opening 17. This opening 17 is utilized for the admission of the cleansing liquid into the container.

5 While I have illustrated and described the preferred form of construction for carrying my invention into effect, this is capable of variation and modification without departing from the spirit of the invention. I, therefore, 10 do not wish to be limited to the precise details of construction set forth, but desire to avail myself of such variations and modifications as come within the scope of the appended claims.

15 Having thus described my invention, what I claim as new and desire to protect by Letters Patent is:

1. A device for cleansing a radiator air vent comprising a body providing a container 20 and having an opening formed in one wall thereof and provided with opposite corresponding wall portions capable of being manually compressed or flexed, and means mounted in said opening to connect said body and the air vent.

2. A device for cleansing a radiator air vent comprising a body providing a container and having an opening formed in one wall thereof and provided with opposite corresponding wall portions capable of being manually compressed or flexed, and means mounted in said opening to connect said body and the air vent, said means including a ring member mounted in the opening and having a threaded opening adapted to receive a threaded portion of said vent.

In testimony whereof I affix my signature.
CHARLES E. REDFIELD.
